UNITED STATES PATENT OFFICE

RICHARD A. ZEIDLER, OF SECAUCUS, NEW JERSEY, ASSIGNEE TO PASS & SEYMOUR, INC., OF SYRACUSE, NEW YORK, A CORPORATION OF NEW YORK

DESIGN FOR A WALL FIXTURE

Application filed September 21, 1929. Serial No. 32,824. Term of patent 7 years.

To all whom it may concern:

Be it known that I, RICHARD A. ZEIDLER, a citizen of the United States, and resident of Secaucus, county of Hudson, State of New Jersey, have invented a new, original, and ornamental Design for Wall Fixtures, of which the following is a specification, reference being had to the accompanying drawing, forming a part thereof, and in which:

I claim:

The ornamental design for a wall fixture substantially as shown.

RICHARD A. ZEIDLER.
